UNITED STATES PATENT OFFICE

ERNEST FISCHER, OF NEW YORK, N. Y., ASSIGNOR TO AMERICAN SAFETY RAZOR CORPORATION, OF BROOKLYN, NEW YORK, A CORPORATION OF VIRGINIA

DESIGN FOR A RAZOR HANDLE

Application filed December 10, 1930. Serial No. 37,930. Term of patent 14 years.

To all whom it may concern:

Be it known that I, ERNEST FISCHER, a citizen of the United States, residing in New York, county and State of New York, have invented a new, original, and ornamental Design for a Razor Handle, of which the following is a specification, reference being had to the accompanying drawing, forming part thereof.

I claim as my invention:

The ornamental design for a razor handle substantially as shown.

ERNEST FISCHER.
